A. HULSMANN

AMUSEMENT APPARATUS

Filed April 14, 1922

UNITED STATES PATENT OFFICE.

ANTON HULSMANN, OF SAN FRANCISCO, CALIFORNIA.

AMUSEMENT APPARATUS.

Application filed April 14, 1922. Serial No. 552,462.

To all whom it may concern:

Be it known that I, ANTON HULSMANN, a citizen of Germany, residing at San Francisco, in the county of San Francisco and State of California, have invented new and useful Improvements in Amusement Apparatus, of which the following is a specification.

This invention relates to an amusement apparatus designed for entertaining and exercising and comprises a playing area having an objective player at one end thereof adapted to be a target for a missile throwing player, with means under the control of the objective player for deflecting the aim of the missile throwing player.

One of the objects of this invention is to provide novel supporting means for the legs of the objective player, the said supporting means being connected to a box-like structure upon which the player lies in a prone position.

This apparatus has various details tending to simplicity and cheapness of construction, strength and durability and the feature of hiding from the view of the spectator practically all of the mechanism that accomplishes the deflection of the aim of the missile throwing player.

Other objects and advantages will be apparent during the course of the following description.

In the accompanying drawings forming a part of this specification, and in which like numerals are employed to designate like parts throughout the same,

Fig. 1 is a perspective view of the amusement apparatus constructed in accordance with my invention,

Fig. 2 is a side elevation of the control mechanism for deflecting the aim of the missile throwing player part of the playing area, and its associated structure being broken away,

Fig. 3 is a bottom plan view of the mechanism with part of the platform being broken away, and

Fig. 4 is a perspective view of the means for supporting the legs of the objective player.

In the accompanying drawings wherein for the purpose of illustration is shown a preferred embodiment of my invention, the numeral 5 designates a playing area as a whole, which comprises a substantially rectangular platform 6 having positioned there-

on adjacent its rear end, a box-like structure 7, having mounted on its upper surface a body rest 8 upon which a player 9 herein described as the objective, is adapted to lie in a prone position. The legs of the player are supported in an elevated position by spaced leg rests 10 and 11, which are suspended from an L shaped rod 12 which has its lower extremity secured to the box-like structure. By virtue of the player assuming this grotesque position the amusement apparatus as a whole, is rendered more entertaining and interesting.

On the opposite end or front end of the platform there is mounted a counter 13 provided with a compartment 14 in which the missile throwing player (not shown) stands with his feet resting on a stand 15. The missiles or aerial projectiles are herein designated by the numeral 16 and are shown as positioned on the upper surface of the counter 13.

In order that the platform may be raised from the ground so as to allow mechanism (to be hereinafter described) to move freely thereunder, I have supported the platform by beams 17 and spaced supports 18 and 19 in the platform, the supports 18 and 19 being connected by a base board 20. While I have shown the platform raised from the ground it is to be noted that the beams and supports can be readily eliminated with the flooring of a hall or room serving the purpose of the platform and thus have most of the mechanism freely controllable under the flooring.

In order that the arm of the missile throwing player may be deflected when he is in the act of impelling the aerial projectile towards the objective player and thus produce hilarity and amusement, I have fixedly mounted the stand 15 on a vertically disposed stub shaft 21 which penetrates the platform 6 and in turn has its lower extremity freely movable in the baseboard 20. To this shaft for the purpose of actuating the same, there is secured a link arm 22 which in turn has connected thereto one extremity of a connecting rod 23, with the other end of the rod secured to a lever 24 under the control of the objective player 9. It will be noted that this lever extends through an opening 25 formed in the platform 6 and is pivoted at 25' to a plate 26 in turn connected to the box-like structure 7. From this construction it will be apparent

that movement imparted to the lever 24 will be transmitted through the rod 23 to the link 22 then to the shaft 26 and finally to the table 15. A consequent arcuate or partial rotatable movement of the table will tend to either throw the player standing thereon off balance or effectively deflect his aim as he impells a missile toward the objective player.

10 While the objective player is here shown as prone and practically helpless to avoid a carefully aimed missile, nevertheless, it will be obvious that he can readily move his body to the right or left which act together with the consequent disturbing of the equilibrium of the player on the platform, due to the manual actuation of the lever 24 by the objective player will minimize the latter's chances of being hit.

20 It is to be understood that the form of my invention herewith shown and described is to be taken as preferred example of the same, and that various changes in the shape, size and arrangement of parts may be resorted to without departing from the spirit of the invention or the scope of the subjoined claims.

Having thus described my invention, I claim:—

30 1. In an amusement apparatus of the character described, the combination with a platform, of a box-like structure positioned adjacent one end of said platform and adapted to support a player in a prone position thereon, a stand positioned adjacent the opposite end of said platform and

adapted to support a missile throwing player thereon, mechanism under the control of the first mentioned player and connected to said stand for deflecting the aim 40 of the missile throwing player, said mechanism comprising a stub shaft for supporting said stand, a baseboard secured to the underside of said platform and having the lower extremity of the shaft freely mounted therein, a link arm connected to said stub shaft, a pivoted lever under the control of the objective player, and a cross rod connecting said lever and said link arm.

2. In an amusement apparatus of the 50 character described, the combination with a platform, of a box-like structure positioned adjacent one end of said platform and adapted to support a player in a prone position thereon, a stand positioned adjacent the opposite end of said platform and adapted to support a missile throwing player thereon, mechanism under the control of the first mentioned player and connected to said stand for deflecting the aim of the missile throwing player, said mechanism comprising a stub shaft for supporting said table, a link arm connected to said stub shaft, a pivoted lever under the control of the objective player, a cross rod connecting said lever and said link arms, and means connected to said box-like structure for holding the legs of the objective player in an elevated position.

In testimony whereof I affix my signature. 70

ANTON HULSMANN.
